DESIGN FOR A LIGHTING FIXTURE

Henry L. Logan, New Rochelle, N. Y., assignor to
Holophane Company, Inc., New York, N. Y., a
corporation of Delaware

Application August 3, 1940, Serial No. 94,185

Term of patent 14 years

To all whom it may concern:

Be it known that I, Henry L. Logan, a citizen
of the United States of America, and a resident
of New Rochelle, in the county of Westchester
and State of New York, have invented a new,
original, and ornamental Design for a Lighting
Fixture, of which the following is a specification,
reference being had to the accompanying draw-
ing, forming a part thereof.

The single figure in the drawing is a perspec-
tive view of the lighting fixture, showing my new
design.

The dominant features of my design reside in
the portions shown in full lines.

I claim:

The ornamental design for a lighting fixture,
as shown and described.

HENRY L. LOGAN.
